UNITED STATES PATENT OFFICE.

GEORGE H. McFEATERS, OF JOHNSTOWN, PENNSYLVANIA, ASSIGNOR TO THE LORAIN STEEL COMPANY, A CORPORATION OF PENNSYLVANIA.

CONTACT-BOX FOR ELECTRIC RAILWAYS.

No. 890,866.

Specification of Letters Patent.

Patented June 16, 1908.

Application filed June 6, 1905. Serial No. 263,933.

To all whom it may concern:

Be it known that I, GEORGE H. McFEATERS, of Johnstown, in the county of Cambria and State of Pennsylvania, have invented a new and useful Improvement in Contact-Boxes for Electric Railways, of which the following is a full, clear, and exact description, reference being had to the accompanying drawings, which form a part of this specification.

My invention has relation to certain new and useful improvements in contact boxes for electric railways, and more particularly to contact boxes of the general character described and claimed in my Patent No. 618,179 dated Jan. 24, 1899.

The objects of my invention are, to increase the current-carrying capacity of the box to adapt it to roads operating heavy cars or trains requiring a more or less heavy current; to provide means of novel and simple character for supporting and securing the sealed vessel or cup which contains the circuit closing devices, and for electrically connecting the cup to the surface contact portion of the box; also to provide means for readily renewing the said contact portion.

A further object is to improve the magnetic circuit of the box.

With these objects in view, my invention consists in the novel construction, arrangement, and combination of parts, all substantially as hereinafter described and pointed out in the appended claims, reference being had to the accompanying drawings, in which

Figure 1, is a plan view of a contact box embodying my invention, Fig. 2, is a sectional view on the line II—II of Fig. 1; Fig. 3 is a similar view on the line III—III of Fig. 1; Fig. 4, is a perspective view of the supporting frame; Fig. 5 is a plan view of the box cover with the magnetic and non-magnetic portions separated; Fig. 6, is an enlarged detail sectional view of one of the contacts; Fig. 7, is a plan view of an armature, showing a modified arrangement of contacts; Fig. 8, is a sectional view on the line VIII—VIII of Fig. 7; Fig. 9 is a similar view on the line IX—IX of Fig. 7; Fig. 10, a transverse vertical section of the central portion of the box cover with the cup attached, (with the contacts removed) and illustrating a different method of securing the cup; Fig. 11, a plan view of the cup supporting and attaching frame of

Fig. 10; and Fig. 12, a section of the same on the line 12—12, of Fig. 11.

The numeral 1 designates the body of the box, having a cavity in which is seated the sealed insulating cup 2.

3 is a filling of insulating material; 4, 4, the magnetic portions of the box cover, and 5, 5^a, the central non-magnetic portions.

6, designates the bolts which secure the cover; 7 designates the supply cables which enter the box by means of the sleeve 8, and are secured in a terminal plug 9, supported in an insulator 10.

11 designates any suitable detachable connection between the plug 9 and the conductor plug 12 embedded in the bottom of the cup 2.

The cup 2 is constructed in two sections, as in my said patent, but these sections are now secured together and the cup supported in a different manner from that shown in said patent. The two sections have the abutted flanges 13, perforated for securing screws 14. In the construction shown in Figs. 1 and 2, these screws pass through the abutted flanges from the top, and engage at their lower portions the inturned horizontal flange 15, of a frame 16, which flange also engages the under surface of the flange 13 of the lower cup section. The frame 16 has extended perforated lugs 17, to receive screws or studs 18, which pass up into the portions 4 of the box cover. In this manner, the cup is securely supported in the said frame, and the whole is rigidly attached to the cover.

19 designates the armature, which is in the form of a thin flat plate normally resting on lugs 19^a, and upon which are mounted the movable contacts 20, of which two are shown in Figs. 2 and 3. These contacts preferably consist each of a button or disk of carbon seated in a holder 21 of conducting material, depressed at its central bottom portion to form a convex projection 22, which fits in a corresponding depression 23 formed in the armature. These interfitting bearing portions 22 and 23 are perforated to receive an attaching screw 24, formed with a rounded head portion seating within the depression 22. The contacts 21 are electrically connected with the conductor 12, in the bottom of the cup, by means of flexible conductors 25, which consist preferably of a single piece of metallic ribbon whose central portion is secured to the conductor 12, and whose

folded end portions are secured to the screws 24, by means of the clamping nuts 26.

27, 27 designate two fixed contacts which are secured to conducting plugs 28, embedded in the top portion of the cup. Covering said top portion is a thin sheet 28^a, of copper or brass, which is brazed to the plugs 28, and which is also secured to the cup by means of the screws 14, above described. 10 This sheet metal cover performs two functions: First, it protects the insulating material of the cup from the softening and deteriorating effect of any water which may collect above the cup; and second, it forms the 15 electrical connection between the plugs 28, and the cover with which it is in contact and to which it is also connected through the frame 16.

It will be apparent from the foregoing, and 20 from the drawing, that the two contacts 21 are in multiple or parallel relation, thereby largely increasing the current-carrying capacity of the cup, as well as sub-dividing the arcs formed between the fixed and movable 25 contacts. This is one of the main features of my invention. It will also be noted that the manner in which the movable contacts 21 are attached to the armature, permits each contact an individual adjusting movement whereby it may come into good contact relation with the corresponding fixed contact. My invention contemplates the employment of any desired number of contacts in multiple. I have, for illustration, 30 in Figs. 7, 8 and 9, shown an armature provided with four contacts 21. These contacts are connected in pairs by means of the conductors 29, to which the flexible conductors 25 are connected, as shown in Fig. 9. 40 To facilitate the connection of the ribbon 25 to the plug 12, the former may be provided with key-hole shaped slots 30 (see Fig. 7) to engage the heads of the screws 31, which are secured in said plug. 32 designates small 45 holes which may be filled with solder to further insure a good electrical connection between the ribbon 25 and the said plug 12.

By reference to Fig. 5, it will be seen that the central non-magnetic portion of the box 50 cover, has the narrow central portion 5^a, and the wider end portions 5. Inasmuch as the current collecting shoe of the car engages the portion 5^a, this portion is subject to considerable wear, and its surface part is therefore made removable. This is accomplished, as shown in Fig. 10, by forming it with a flange portion 5^b, which is anchored in a retaining body 5^c of spelter, or similar material, which can be readily cut out to permit the 55 said part to be removed; or said part 5^a may be made in wedge form and driven into a seat formed in the main part 5, as shown in Figs. 1, 2 and 3.

The purpose of making the central portion 60 of the non-magnetic cover narrower

than the end portions, is to contract the magnetic lines of force through this central portion, which lies directly over the armature.

In Fig. 5, the arrows in full lines indicated the travel of the magnetic lines of force 70 through the magnetic portions 4, 4 of the cover, while the dotted arrows indicate the travel of the lines of force below the non-magnetic portion 5, and thereby passing through the armature 19. 75

Figs. 10, 11 and 12 show a modified arrangement for supporting the cup and securing it to the cover. In these figures, the cup is surrounded by a frame 32, and ring 33. The frame 32 has lugs 34, which extend up into the 80 non-magnetic portion 4 of the cover, and are anchored therein in the bodies 35, of spelter or similar material, the said lugs having grooves 36 and perforations 37 for increasing the retaining hold of the spelter. Screws 38 (corresponding to the screws 14 of the construction shown on Sheet 1) pass up through the ring 33, the flanges of the cup sections, and the metallic covering sheet 28, into the said frame 32. 85

By using either of the means described for 90 securing the cup to the box cover, the cup is rigidly secured to the box cover in a manner which avoids all strains tending to separate the two portions of the cup.

I do not desire to limit myself to the precise details of construction, arrangement and combination which I have herein shown and described, as various changes may be made therein without departing from the spirit and scope of my invention. 95

Having thus described my invention, what I claim as new and desire to secure by Letters Patent is:—

1. In a contact box for electric railways, a box with a cup therein, the box cover, a frame surrounding the cup below, a supporting flange, and means to secure the frame to the cover, in combination with a movable contact within the cup, and a flexible conductor connected to the contact. 105

2. In a contact box for electric railways, a box provided with a cover, a two part cup therein, each part having a horizontal abutting flange, a frame supporting the cup beneath the flange, and suspended from the box cover in combination with a movable contact within the cup, and a flexible conductor secured to the contact. 115

3. In a contact box for electric railways, a box provided with a cover, a two part cup therein, each having a horizontal abutting flange, a frame supporting the cup beneath the flange, and suspended from the box cover, screws extending through the flanges and engaging the frame, in combination with a movable contact, and a flexible conductor secured to the contact. 120

4. In a contact box for electric railways, a box provided with a cover, a two part cup within the box, having a movable contact 125

secured to a flexible conductor therein, a frame supporting the cup, and secured to the cover, and means whereby the cup sections are secured to each other and to the frame.

5. In a contact box for electric railways, a box provided with a cover, a cup of insulating material within the box, and a conducting plug embedded in the upper portion of 10 the cup, a movable contact secured to a flexible conductor within the cup, and a metallic cover in electrical connection with the plug and the box cover.

6. In a contact box for electric railways, 15 the box cover composed of a central portion of nonmagnetic material, and side portions of magnetic material, said nonmagnetic portion being narrower at its central part than at its ends, and a movable contact secured to 20 a flexible conductor to connect the box cover with the supply cable.

7. In a contact box for electric railways,

the box cover composed of a central portion of nonmagnetic material, and side portions of magnetic material, said nonmagnetic portion 25 being narrower at the central part than at its ends, and said central part having a removable surface portion, and a movable contact secured to a flexible conductor to connect the box cover with the supply cable. 30

8. A contact box cover having a central portion of nonmagnetic material provided with a seat therein, and a wedge shaped surface or contact portion removably driven into the said seat, and a movable contact secured 35 to a flexible conductor to connect the box cover with the supply cable.

In testimony whereof, I have affixed my signature in presence of two witnesses.

GEORGE H. McFEATERS.
